UNITED STATES PATENT OFFICE.

THEODORE SCOTT, OF MONTICELLO, INDIANA.

VAULT-COVER, &c.

SPECIFICATION forming part of Letters Patent No. 793,545, dated June 27, 1905.

Application filed October 13, 1904. Serial No. 228,365.

To all whom it may concern:

Be it known that I, THEODORE SCOTT, a citizen of the United States, residing at Monticello, in the county of White and State of Indiana, have invented new and useful Improvements in Vault Covers and Seals, of which the following is a specification.

This invention has reference to safes and their vaults and means for securing the safes in their vaults to prevent them from being tampered with by burglars or other wrongdoers.

I mention the invention as having relation to safe-covers; but it will be apparent that it may be employed in any vault as well where safety of the contents of the same is a matter of concern.

It is the particular object of the invention to provide safety-covers which shall prevent burglars and other wrongdoers from reaching the safe or contents of the vault by means of explosives.

The invention will be fully set forth in the specification hereinafter given in view of the annexed drawings, forming a part of the specification, in which the same symbols of reference designate the same parts or features, as the case may be, wherever they occur.

In the drawings, Figure 1 is a vertical sectional view of a safe-vault with the safe therein at the bottom, though as regards some parts of the invention it might as well be regarded as a casket or other object. Fig. 2 is a diagram, on a larger scale, of a vault-cover. Fig. 3 is a side view of the same, showing also the means for locking the cover in position and other adjuncts. Fig. 4 is a view of a vault with a safe therein, showing a plurality of safe-covers below ground.

In the drawings, 10 designates the inner casing of the vault, which may be as deep and be surrounded by as great an area of cement as desired. At the top of the vault there is a windlass 11 of any suitable construction for raising and lowering the safe 12 or other object in the vault. The entrance to the mouth of the vault may itself be made within a strong substantial structure 13 within a bank or other building. The casing to the vault

may be of chilled metal or other material and 50 may be as thick and strong as desirable, stronger in one part than another, if desired, and otherwise left for variance in form and arrangement to the suggestions of mechanical skill. At points in the vault-shaft below 55 the surface and as frequently as may be desired the casing 10 may be provided with a ledge 14, upon which may rest a cover 15, with a packing 16 of any suitable character to render it dust and water proof interposed 60 between the cover and ledge, so that any explosive cannot be worked through from above the cover to any point below it. Connected with the casing beneath each ledge is a lug or catch 16, adapted to be engaged by a latch 65 17, constructed as a bell-crank lever pivoted to the under side of the cover, the shorter arm 18 acting as a catch and the longer arm 19 overweighted and extending down to a point so low that when the safe is lifted it will engage the longer arm and move it far enough 70 to unlatch the cover, so that on its further movement upward it may carry the cover with it, one cover lifting the next cover above, and so on, the reverse movement replacing 75 the covers.

By the means described the covers 15 are self-locked in place, not only against being released from above, but against a possibility of having explosives worked through under 80 the cover and there exploded, so as to get it out of the way.

It is repeated that there may be as many covers employed as is deemed desirable or necessary.

At the bottom of the vault where the safe or other matter or object is deposited the casing may be made heavier or thicker to still better protect it, and it is provided with a tight packing and covering, so that explosives 90 cannot be made to reach it, and if it be a safe to be released by a time-lock mechanism the latter may be placed beneath the safe to still the more greatly assure of its being kept safe against being reached by burglars.

Objects properly placed in a vault equipped with my improvements will not only be mechanically secured against being tampered

with, but they will be tightly secured against the introduction of explosives and other things as well.

It is contemplated that the vaults shall be 5 formed in the ground and run in a vertical manner. Still these things are unimportant, so long as they are made burglar-proof and tightly secured, as described, or so that an essential part of the substance of the improvement flows from the structure.

It is to be noted that my improvements are for the most part adapted to be employed in cemetery-vaults as well as in safes, and I propose to take advantage of these and all other 15 proper uses that may be made of it.

It is to be understood that in my improvements the vault-covers are all located well underground in contradistinction to being placed at the surface.

20 In another application for a patent, filed of even date herewith, Serial No. 228,366, I have shown and described a disappearing safe in which a cover is represented resembling the plurality of covers and associated parts here- 25 in shown, and reference may be had thereto; but in the said other application no claim is made to said cover or covers claimed herein.

What is claimed is—

1. A combined vault and disappearing safe 30 comprising a cemented area to a suitable

depth, a safe-vault formed in said area, a safe in said vault, a plurality of covers to the safe, at intervals within the vault, below the surface, provided with locks or fastenings on their under sides, and releasable only by the action 35 of the safe thereon from below.

2. A combined vault and disappearing safe comprising a cemented area to a suitable depth, a safe-vault formed in said cemented area, a plurality of covers to the safe, at intervals within the vault, below the surface, provided with locks or fastenings on their under sides and releasable only by the action of the safe thereon from below, each succeeding cover considered from above downward, be- 40 ing of less diameter than those above.

3. A combined vault and disappearing safe comprising a cemented area to a suitable depth, a safe-vault formed in said cemented area, a cover to the safe in the vault, below the 50 surface, provided with fastening means releasable only by the action of the safe thereon from below.

In testimony whereof I have signed my name to this specification in presence of two sub- 55 scribing witnesses.

THEODORE SCOTT.
